United States Patent

Des. 242,214
Patented Nov. 9, 1976

242,214

FILE HOLDER

Elof Granberg, 531 Canal St., San Rafael, Calif. 94901

Filed July 25, 1975, Ser. No. 599,047

Term of patent 14 years

Int. Cl. D8—05

U.S. Cl. D8—94

FIG. 1 is a side elevation showing my design of a file holder;

FIG. 2 is a top plan view thereof;

FIG. 3 is a bottom plan view thereof;

FIG. 4 is a first end view thereof from the left of FIG. 2;

FIG. 5 is the opposite end view thereof from the right of FIG. 2.

The broken line disclosure of a file in FIG. 1 is for illustrative purposes only.

I claim:

The ornamental design for a file holder, as shown and described.
